LOCKING MECHANISM

Sven Larsson, Ekeby, Almby, Sweden

Application January 15, 1945, Serial No. 572,942
In Sweden November 16, 1943

10 Claims. (Cl. 70—150)

1

The present invention refers to a locking mechanism of the type, comprising a tubular cylinder enclosing a slidably fitted bolt, the retraction of which is effected against spring action by means of a rotatable disk disposed behind the locking bolt in the tubular cylinder. Such locks are known per se and are advantageous inasmuch as the mounting thereof incurs but low costs, it being possible to bore a hole in a door for the reception of the tubular cylinder and avoid otherwise necessary chiselling out of the mortise.

A more particular object of the invention is to provide a simplified and cheaper form of such a locking mechanism which, if desired, may be provided with a tumbler for the bolt.

The special characterizing feature of invention is that the disk bears on a bearing member provided between the disk and the bolt in the tubular cylinder and that the disk is provided with a backwardly or inwardly extending cam adapted to cooperate with a cam track on a member connected to the bolt.

So that the invention may be readily understood and easily put into effect a preferred embodiment thereof is illustrated by way of example only, in the accompanying drawings in which:

Fig. 1 is a vertical section through door-case, a door and a locking mechanism according to the invention mounted therein, the bolt being shown in locking position.

Fig. 2 is a similar sectional view, the lock being in unlocking or receded position.

Fig. 3 shows a horizontal section through the parts shown in Figs. 1 and 2.

Fig. 4 is a side view of the lock housing.

Figs. 5 and 6 show two different cross sections taken along the lines V—V and VI—VI respectively in Fig. 1.

Fig. 7 shows a plan view of an abutment element for a spring adapted to bear on the bolt.

Fig. 8 shows a section of the bolt.

Fig. 9 is a piece of sheet metal intended to be doubled along the dotted lines in the middle and thereby form a guide.

Figs. 10 and 11 are a side view and a cross section respectively of a lateral bar.

Figs. 12—25 show seven other component parts of the locking mechanism, partly as seen from above and partly as seen from the side, to wit, a bearing member, a locking element, a stemmed member, a disk, an end-plate, a stud, and a tubular lock housing.

Fig. 26 shows a longitudinal section of the outer cylinder shown in Figs. 24 and 25.

2

Fig. 27 is a view of those parts rigidly connected to the bolt in the locking mechanism.

Fig. 28 is a view of another form of the bolt and part of the elements rigidly connected thereto.

Fig. 29 is a section along the line XXIX—XXIX in Fig. 28.

Fig. 30 is another form of the abutment element.

Fig. 31 is a section along the line XXXI—XXXI in Fig. 30.

Figs. 32 and 33 show two different forms of the key-bit.

Fig. 34 shows another form of the disk and the end plate.

In Figs. 1—3 the reference numeral 1 designates the door in one of the vertical edges of which the locking mechanism according to the invention is mounted, and which at the opposite edge thereof is hinged on the other side (not shown) of the door case 2. The door case 2 is provided with a recess 3 registering with a bolt 4, adapted to protrude into the recess when the door is closed. The bordering edges of the recess 3 are strengthened in the usual way by means of a mounting 5 adapted to be secured in the door case 2 by means of screws or the like (not shown).

The door 1 (Fig. 3) is provided with two horizontal intersecting bores or mortises 6, 7, of which the one 6 extending from the edge of the door is adapted to receive the lock housing, while the other bore 7 is adapted to receive the spindle 8 of a handle 9. The door 1 is furthermore provided with a bore or mortise 10 for permitting the introduction of a key 11 into the lock housing. The reference numeral 12 designates a plate which surrounds the mouth of the mortises 7, 10, and which is fastened to the door 1 by one or several screws 13, or by any other suitable means.

The lock housing consists of an externally and internally tubular cylinder 14 adapted to enclose all parts of the locking mechanism. In order to enable the insertion of the key 11 and the spindle 8 of the handle 9 into the locking mechanism, the cylinder 14 is provided at both of its two opposite sides with two separate slots, or with a common longitudinal slot 15, as will be apparent from Figs. 4, 6, 24 and 26.

The cylinder 14 is provided at that end facing the door case 2 with an annular outer flange 16 adapted to be let into the edge of the door in a comparatively shallow recess which is coaxial with the mortise 6 but of greater diameter than the latter. In the form shown, the flange 16 is not provided with any screw holes for

fastening the flange to the edge of the door, but serves as an ordinary stop flange. The flange may, of course, be provided with screw holes, but as no material advantage is to be gained from securing it by screws or the like, the provision of such holes would only unnecessarily enhance the manufacturing costs of the lock. Moreover, the flange 16 may be altogether omitted because the locking mechanism, as will be apparent from the following description, may be held in the slot 6 by means of a handle 9 alone.

The cylinder 14 is provided at its other end with an inwardly directed flange 17 adapted to provide an abutment for certain non-displaceable parts of the locking mechanism in a manner described herebelow.

As will be apparent from Fig. 8 the bolt 4 has a backwardly or inwardly directed bifurcated extension, the two forks 18, 19 of which (Figs. 3, 27, 28 and 29) grip the end of a guide, consisting of two parallel elements or shanks 20, 21. This guide is preferably made from a single blank, which is doubled along dash and dot lines intermediate its ends, as indicated in Fig. 9. Between the shanks 20, 21 there is an interjacent member 22 which, as will be apparent from Figs. 1, 2, 16, 27, 28 and 29 is provided at its inward end with an eccentrically located, inwardly extending stem 23 provided at its free end with an oblique surface 24, the purpose of which will be apparent later on in the description.

The parts 18-22 are provided with holes 25, 26 and 27 through which extends a stud 28 by means of which the parts 18-22 are held together. Each of the elements or shanks 20 and 21 is provided with a longitudinal slot 29 and 30 respectively, adapted to permit the passage of interalia the key 11 and the spindle 8 of the door handle 9 therethrough. Towards that end proximate the holes 26, the slots 29 and 30 are reduced to slits 31 and 32 respectively, the purpose of which will be apparent later on in the description.

At one end of the shanks 20 and 21 there is in spaced relationship to the holes 29 and 30 a ledge 33, forming a seat for the one end of a spring 34 when the locking mechanism is dismounted in that manner shown in Figs. 27-29. No matter whether the mechanism is disarticulated or dismounted in the above mentioned manner or whether it is completely assembled, the other end of the spring 34 is in continuous abutting engagement with an inwardly facing ledge formed by the inner surface of the bolt and a reduced portion of the bolt, which portion extends inwards and is adapted to guide the spring 34 (see Figs. 1-3, 5, 6, 8 and 27). As the guiding of the spring 34 by the shanks 20, 21 and by the inner wall of the tubular casing 14 will in most cases be sufficient, the bolt may also take the form shown in Figs. 28, 29, in which it is given a uniform diameter, and in which the spring abuts the inwardly facing end surface of the bolt. The last-mentioned form of the bolt is cheaper to fabricate and more practical in use inasmuch as it facilitates the insertion of the stud 28, because the spring does then not obstruct the hole 26 adapted to receive the stud 28.

At the opposite end of the guide member 20, 21, is a rigidly mounted end-plate 35, one form of which is illustrated in Figs. 20 and 21, another form thereof being shown in Fig. 34. The end-plate 35, one end of which abuts the doubled portion 36 (Fig. 9) of the guide member 20, 21, is fastened to the guide member 20, 21 by means

of a pin 37 extending through the holes 38, 39 and 40 provided in the parts 20, 21 and 35 respectively. The outwardly facing edge of the end-plate 35 is provided with a recess 41 in which a triangular cam portion of a disk 43 is adapted to engage. The disk 43, one form of which is shown in Figs. 18 and 19 and another in Fig. 34, is provided with a rectangular slot 44 adapted to permit the passage of the likewise rectangular spindle 8 of the handle 9. The form of the disk shown in Fig. 34 is most advantageous if the locking mechanism is to be adaptable for right-handed as well as for left-handedly hinged doors, the locking mechanism then being adaptable for either sort of door simply by turning the outer cylinder 14.

At that circumferential portion facing the mouth of the mortise, the disk bears on the inwardly facing edge of a bearing member shown 20 by way of example in Figs. 12 and 13. The bearing member 46 is rigidly connected to two slightly channelled lateral bars 47 (Figs. 10, 11, 31 and 32) disposed at either side of the shanks 20, 21. The one end of the lateral bars 47 is adapted always 25 to abut the inner flange 17 of the tubular casing 14, the other end of the lateral bars being adapted normally to form an abutment for a resiliently fixed element when the locking mechanism is assembled; this element will be described later on 30 in the description. In the form shown in the drawings by way of illustration only, the bearing member 46 and the lateral bars 47 are provided with holes or slots 45 and 49 respectively. In order to facilitate the assembly of the lock the 35 bars 47 may be loosely threaded onto a stud 50, which, like the holes 45 and 49, may be of arbitrary cross section e. g. round or, as shown in Figs. 22 and 23, rectangular. In both forms shown in the drawings the bars 47 are moreover provided 40 with key holes 51, 52 and a hole 53 for the spindle 8 of the door handle 9. In the form shown in Figs. 30 and 31 the outer sides of the lateral bars 47 are moreover shaped with horizontal recesses 54 extending inwardly from the outwardly facing 45 edge of the bars, the inner side of the bars 47 being provided with one or more projections, studs, wards 55 or the like which may be produced e. g. by pressing. The purpose of the recesses 54 and the projections 55 will be described together with 50 the key-bit later on in the description.

When the lock is assembled, the bearing member abuts a U-like locking element 56, the shape of which is shown in Figs. 14 and 15 and which in its turn abuts an abutment element 57, which 55 element is under the influence of a spring 34 and has the special form shown in Fig. 7 and abuts the outer ends of the channel-like bars 47. The locking element 56 is adapted to be actuated by a key 11 so that it may be moved from that position 60 in which it is shown in solid lines in Fig. 1 and in which the bolt 4 cannot recede further than to a position in which the stem 23 of an intermediate element 22 abuts the outer edge of the locking element, to that position shown with dotted lines 65 in Fig. 1, and with solid lines in Fig. 2, in which latter position the bolt 4 may be totally withdrawn from the recess 3 in the door case 2. The locking element 56 is fixed in its two locking positions by means of its two extremities 58, 59 engaging one of two pairs of notches 60, 61 provided in the outwardly facing edge of the bearing member 46. In order to facilitate the passage 70 of the locking element past the stem 23 of the intermediate element 22 during the travel of the locking element from the one position to the 75

other, during which travel it momentarily compresses the spring 34 a negligible amount, the locking element is provided with an oblique surface 62. The abutment element 57 is provided with two pairs of notches 63, 64 in which the two shanks 20, 21 are adapted to engage and thereby guide the abutment element along the edges of the slits 31. The upper finger 65 of the two fingers 65 and 66 remaining between the notches and disposed between the shanks 20, 21 of the 10 guide, is truncated in order to enable the stem 23 of the intermediate element 22 to pass through the abutment element when the bolt 4 is to be reected.

The key-bit 67 may be provided with one or 15 more grooves 68 parallel to the stem of the key 11 as shown in Fig. 32, this form being advantageous inasmuch as the cost of production of the key is then comparatively cheap. This form is, however, disadvantageous inasmuch as it permits but a relatively small range of variation of the shape of the key-bit 67, so that one and the same key will not fit or match more than a limited number of locks. Another disadvantage with this last-mentioned form is that a variation of the shape of the key-bit 67 will necessitate also a corresponding variation of the slot 51 in the channeled bars 47, which will necessitate rather an excessive number of pressing tools.

Fig. 33 shows another form of the key-bit 67 of 30 the key 11, which bit permits a greater range of variations and at the same time permits a key hole 52 of one and the same form to be used for all keys. In this form the key-bit is provided with three fingers or wards 69, 70, 71 perpendicular to the stem of the key, the middle ward 70 passing interjacent the two shanks 20 and 21 of the guide when the key is turned, the other two wards passing adjacent the outer sides of the last-mentioned shanks. One or both of the outer 40 wards 69 and 71 are provided on their outer side with notches 72, 73 which are positioned and formed in such a manner that the key on being turned will pass the projections 55 provided on the inner side of the bars 47. In order to obtain a wider range of variation the wards 69, 71 in this embodiment are comparatively long, which is enabled by the recesses 54 in the channeled bars 47, the angular edges of which would otherwise obstruct the turning of the key. In order to widen the range of possibilities still more, the form shown in Fig. 32 may be combined with that shown in Fig. 33.

The locking mechanism or lock is preferably assembled in the following manner: The guide 20, 21, the bolt 4, the intermediate element 22, the spring 34 and the end plate 35 are connected or assembled in the manner shown in Fig. 27. These parts cannot be shifted in relation to one another but are shiftable as an entity in the lock housing. Thereafter the disk 43 is inserted with its cam 42 in the recess 41 of the end plate 35. The abutment element 57 is then inserted in the slots 29 where it is turned through 180° so that the wards 65, 66 will be interjacent the two shanks 20, 21 where after it is urged along the slit 31 where it is held by the hand while the bearing member 46 and the locking element 56 are inserted into position. After these two last-mentioned parts are assembled the disk 43, the bearing member 46, the locking element 56 and the abutment element 57 are held in position by the pressure exerted by the spring 34 on the abutment element 57. The stud 50 is then inserted through the hole 48 in the bearing mem-

ber, whereafter the bars 47 are loosely threaded onto those portions of the stud projecting beyond the shanks 20, 21. Finally all these parts are inserted into the lock housing 14 whereafter the lock is mounted in the door 1 in the usual manner.

The operation of the locking mechanism is as follows: If the disk 43 is turned clockwise by means of the door handle 9 from that position in which it is shown in dotted lines in Fig. 1, the cam 42 will glide along the cam track 41 and urge the guide 20, 21 and the bolt with parts rigidly connected thereto inwardly or backwardly against the action of the spring 34 abutting the abutment element 57, the parts thereby assuming that position shown in Fig. 2. On release of the handle the mechanism will again assume that position shown in Fig. 1.

The door is locked if the locking element is moved by means of the key 11 from the position shown in dotted lines in Fig. 1 to the position shown in solid lines in the same figure.

What I claim and desire to secure by Letters Patent is:

1. A locking mechanism comprising a tubular lock casing mounted in a door; a bolt slidably mounted within the lock casing; a member connected to the bolt and extending into the lock casing; a spring adapted to retain the bolt in protruded position; a plate fixedly mounted on the inner end of the member extending into the lock casing and provided with a cam track, means for rigidly securing said plate in position against movement, a fixed bearing element intermediate the bolt and the plate; a disk having an inwardly directed cam portion, the disk bearing on the fixed bearing member, the cam portion of the disk being in actuating engagement with the cam track, a spindle extending into the casing and operatively connected to the disk, and a handle mounted on the spindle.

2. A locking mechanism comprising a tubular lock casing mounted in a door; a bolt slidably mounted within the lock casing, a member connected to the bolt and extending into the lock casing; a spring adapted to retain the bolt in protruded position, a plate mounted on the inner end of the member extending into the lock casing and provided with two cam tracks, means for rigidly securing said plate in position against movement, a fixed bearing element intermediate the bolt and the plate, a disk having an inwardly directed cam portion, the disk bearing on the fixed bearing member, the cam portion of the disk being in actuating engagement with a cam track, a spindle extending into the casing and operatively connected to the disk, and a handle mounted on the spindle.

3. A locking mechanism comprising a tubular lock casing mounted in a door; a bolt slidably mounted within the lock casing; a member connected to the bolt and extending into the lock casing, said member comprising a pair of slotted parallel guide elements; a plate mounted interjacent the inner ends of the slotted guide elements and provided with a cam track, means for rigidly securing said plate in position against movement, a bearing element fixed intermediate the bolt and the plate; a disk having an inwardly directed cam portion and adapted to bear on said bearing member and actuatingly to engage the cam track on the plate, the disk and the bearing member being also disposed interjacent said slotted guide elements, a spindle extending into the casing and through a slot in the slotted guide

members and operatively connected to the disk, and a handle mounted on the spindle.

4. A locking mechanism comprising a tubular lock casing mounted in a door; a bolt slidably mounted within the lock casing; a member connected to the bolt and extending into the lock casing, said member comprising a pair of parallel slotted guide elements; a plate mounted interjacent the inner ends of the slotted guide elements and provided with a cam track, means for rigidly securing said plate in position against movement, a fixed bearing member intermediate the bolt and the plate; a disk having an inwardly directed cam portion and adapted to bear on said bearing member and actuatingly to engage the cam track on the plate, the disk and the bearing member being also interjacent the slotted guide elements, an abutment element; a spring extending between and bearing on the abutment element and the proximate end surface of the bolt, the abutment element being shiftable a limited amount along the guide elements against the action of the spring, from a normally fixed position, a spindle extending into the casing and operatively connected to the disk, and a handle mounted on the spindle.

5. A locking mechanism comprising a tubular lock casing mounted in a door; a bolt slidably mounted within the casing; a member connected to the bolt and extending into the lock casing, said member comprising a pair of parallel slotted guide elements; a plate mounted interjacent the inner ends of the slotted guide elements and provided with a cam track, means for rigidly securing said plate in position against movement, a fixed bearing member intermediate the bolt and the plate; a disk having an inwardly directed cam portion and adapted to bear on said bearing member and actuatingly to engage the cam track on the plate, the disk and the bearing member being also interjacent the slotted guide elements, an abutment element, a pair of lateral bars abutting the inwardly facing surface of the abutment element and the inner end of the tubular lock casing, a spring extending between and bearing on the abutment element and the proximate end surface of the bolt, the abutment element being shiftable a limited amount along the guide elements against the action of the spring from a normally fixed position in which it is held by the lateral bars, a spindle extending into the casing and operatively connected to the disk, and a handle mounted on the spindle.

6. A locking mechanism comprising a tubular lock casing mounted in a door; a bolt slidably mounted within the casing; a member connected to the bolt and extending into the lock casing, said member comprising a pair of parallel slotted guide elements; a plate mounted interjacent the inner ends of the slotted guide elements and provided with a cam track, means for rigidly securing said plate in position against movement, a fixed, slotted bearing member intermediate the bolt and the plate; a disk having an inwardly directed cam portion and adapted to bear on the bearing member and actuatingly to engage the cam track on the plate, the disk and the cam member being also interjacent the slotted guide elements; an abutment element; a pair of slotted, lateral bars abutting the inwardly facing surface of the abutment element and the inner end surface of the tubular lock casing; a stud extending through a slot in the bearing member and in the lateral bars and thereby detachably connecting these parts; a spring extending between and

adapted to bear on the fixed, slotted bearing member and the proximate end surface of the bolt, the abutment element being shiftable a limited amount along the guide elements against the action of the spring, from a normally fixed position in which it is held by the slotted lateral bars; a spindle extending into the casing, and operatively connected to the disk; and a handle mounted on the spindle.

10 7. A locking mechanism comprising a tubular lock casing mounted in a door; a bolt slidably mounted within the lock casing; a stem extending inwardly from the bolt; a member connected to the bolt and extending into the lock casing; 15 said member comprising a pair of parallel slotted guide elements, a plate mounted interjacent the inner ends of the guide elements and provided with a cam track, means for rigidly securing said plate in position against movement, a fixed bearing member intermediate the bolt and the plate; a disk having an inwardly directed cam portion adapted to bear on said bearing member and actuatingly to engage the cam surface on said plate, the disk and the bearing member being interjacent the slotted guide members, a slotted abutment element, a spring bearing on the slotted abutment and the proximate end surface of the bolt, the slotted abutment being shiftable a limited amount along the guide elements against the action of the spring, from a normally fixed position, a locking element disposed between the bearing member and the slotted abutment element and adapted to be shifted by means of a key transversely of the lock casing, from an inoperative position to a position in which it obstructs recession of the stem through a registering slot in the slotted abutment element, a spindle extending into the tube casing and operatively connected to the disk; and a handle mounted on the spindle.

40 8. A locking mechanism comprising a tubular lock casing mounted in a door; a bolt slidably mounted within the lock; a stem extending inwardly from the bolt; a member connected to the bolt and extending into the lock casing, said member comprising a pair of slotted, parallel guide elements; an end-plate fixed interjacent the inner end of the guide elements and provided with a cam track; a fixed bearing member intermediate the bolt and the plate; a disk having an inwardly directed cam portion and adapted to bear on said bearing member and actuatingly to engage the cam surface on said end-plate, the disk and the bearing member being disposed also interjacent the slotted guide members, a slotted abutment element, a spring bearing on the slotted abutment element and the relatively proximate end surface of the bolt, the slotted abutment element being shiftable a limited amount along the guide elements against the action of the spring, from a normally fixed position; a substantially U-like locking element located between the bearing member and the slotted abutment element and adapted to be shifted transversely of the lock casing by the actuating engagement of the key-bit with the inner U-surface, from an inoperative position to a position in which it obstructs recession of the stem through a slot in the slotted abutment element, 60 a spindle extending into the casing and operatively connected to the disk; and a handle mounted on the spindle.

9. A locking mechanism comprising a tubular lock casing mounted in a door; a bolt slidably mounted within the lock; a stem extending in-

wardly from the bolt; a member connected to the bolt and extending into the lock casing, said member comprising a pair of slotted, parallel guide elements; an end-plate fixed interjacent the inner ends of the guide elements and provided with a cam track; a fixed notched bearing member intermediate the bolt and the plate; a disk having an inwardly directed cam portion and adapted to bear on said bearing member and actuatingly to engage the cam surface on said end-plate, the disk and the bearing member being disposed also interjacent the slotted guide members, a slotted abutment element, a spring bearing on the slotted abutment element and the relatively proximate end surface of the bolt, the slotted abutment element being shiftable a limited amount along the guide elements against the action of the spring, from a normally fixed position; a substantially U-like locking element disposed between the notched bearing member and the slotted abutment element and adapted by means of its extremities to cooperate with the notched bearing member and to be shifted transversely of the lock casing by the actuating engagement of a key-bit with the inner U-like surface, from an inoperative position to a position in which it obstructs recession of the stem through a registering slot in the slotted abutment; a spindle extending into the casing and operatively connected to the disk, and a handle mounted on the spindle.

10. A locking mechanism comprising a tubular casing mounted in a door; a bolt slidably mounted within the casing; a stem extending inwardly

from the bolt; a member connected to the bolt and extending into the lock casing, said member comprising a pair of slotted parallel guide elements; a plate mounted interjacent the inner ends of the slotted guide elements and provided with a cam track, means for rigidly securing said plate in position against movement, a fixed slotted bearing member intermediate the bolt and the plate; a disk having an inwardly directed cam portion and adapted to bear on the bearing member and actuatingly to engage the cam track on the plate; the disk and the cam member being also interjacent the slotted guide elements; a spring bearing on the inner end surface of the bolt and the outwardly facing surface of fixed, slotted bearing member; a slotted abutment element adapted to be guided by the slotted, parallel guide elements, a pair of warded and slotted lateral bars abutting the inwardly facing surface of the slotted abutment element and the inner end wall of the tubular casing, the slotted abutment element thereby being held in a definite position from which it may be shifted a limited amount along the guide elements by a suitably warded key-bit against the action of the spring, from an inoperative position in which it is normally held by the warded and slotted bars to an operative position, in which it obstructs the recession of the stem, through a registering slot in the slotted abutment; a spindle extending into the casing and operatively connected to the disk; and a handle mounted on the spindle.

SVEN LARSSON.
